UNITED STATES PATENT OFFICE.

CARL CONRAD, OF ST. LOUIS, MISSOURI.

DESIGN FOR TUMBLERS.

Specification forming part of Design No. **11,238**, dated June 10, 1879; application filed May 15, 1879.
[Term of patent 3½ years.]

To all whom it may concern:

Be it known that I, CARL CONRAD, of St. Louis, in the State of Missouri, have originated a new Design for a Tumbler, of which the following is a full, clear, and exact description, reference being had to the accompanying drawings, making part of this specification.

This invention relates specially to a new design for a tumbler or drinking-glass for beer, ale, and malt liquors.

The object of my design is to obtain a sparkling appearance and effervescent effect for beer, ale, and malt liquors similar to that produced by using champagne-glasses for champagne and similar wines.

In the drawings, Figure 1 is a side elevation. Fig. 2 is a sectional elevation.

A represents my glass or tumbler. The body A', both interior and outside, has the ordinary tapering shape from the top to the line x x, as shown. From the line x x I form the interior to have the bulge or curvature at a, to pre-

sent a surface for impact and produce a fermenting action when the beer, &c., is poured in the glass. From the bulge a the interior is gradually contracted, terminating with the vertical opening a', which exists in the stem of the glass and extends to the base thereof, as shown in Fig. 2. A more complete agitation and fermentation of the entered beer, &c., therefore takes place, producing the sparkling and effervescent effect, which enhances the appearance.

What I claim is—

A design for a tumbler or drinking-glass in which the interior is made to present the curvature or bulge at a and contracted opening a', in the manner above described.

In testimony of said invention I have hereunto set my hand.

CARL CONRAD.
